WILLIAM R. KING, OF PITTSBURGH, PENNSYLVANIA, ASSIGNOR TO WESTINGHOUSE ELECTRIC & MANUFACTURING COMPANY, A CORPORATION OF PENNSYLVANIA

TERMINAL FOR RESISTANCE CONDUCTORS

Application filed July 7, 1928. Serial No. 291,048.

This invention relates to electric heaters and particularly to terminals for resistance conductors.

An object of the invention is to provide a terminal for resistance conductors that shall be simple in construction, efficient in its operation and easily manufactured and installed.

Another object of the invention is to provide a terminal for electric conductors that may be expanded into electrical contact with the conductor.

A further object of the invention is to provide a terminal for sheathed electrically-insulated conductors that may be expanded into electrical contact with the conductor after the conductor has been located in the sheath.

A still further object of the invention is to provide a terminal for electric conductors in which contact is established both by the expanding of the terminal into contact with the conductor and by pressing the conductor against the terminal; and

A still further object of the invention is to provide terminals for resistance conductors in which contact between the terminal and the conductors may be established by pressure.

For a fuller understanding of the invention, reference may be had to the following description taken in conjunction with the accompanying drawings, in which:

Figure 1 is a plan view, partially in section, of a terminal for an electrical-resistance conductor;

Fig. 2 is an end view thereof;

Fig. 3 is a plan view of a detail embodied in the terminal of Fig. 1;

Fig. 4 is an end view of the detail shown in Fig. 3;

Fig. 5 is a plan view of a modified form of the detail shown in Fig. 3;

Fig. 6 is an end view of the detail shown in Fig. 5;

Fig. 7 is a view, in longitudinal section, of an autoclave in which a tubular heater is positioned to be subjected to an atmosphere of steam to convert magnesium metal into magnesium hydroxide;

Fig. 8 is a view, in section, of a portion of a heating unit completely assembled and ready for use after it has been treated in the autoclave shown in Fig. 7;

Fig. 9 is a plan view showing a modification of the terminal structure illustrated in Fig. 1; and

Fig. 10 is an end view thereof.

In the drawing, a terminal 1 for an electrical-resistance conductor 2 is illustrated, 60 which is particularly adapted to sheathed, encased or tubular heating units (see Fig. 8). The terminal 1 comprises a hollow cylinder having a threaded end portion 3, a split end portion 4 and an intervening enlarged portion 5 which may be provided with a knurled surface for a purpose to be hereinafter set forth.

The terminal 1 may be secured to the helix 2 by inserting a metallic pin 6 of oxidizable 70 material, such as magnesium, into the split end portion 4 and then inserting this end portion into the helix. The terminal, having been located as shown in Fig. 1, the pin 6 of magnesium metal may be converted to magnesium hydroxide by subjecting it to the oxidizing effect of steam under pressure. Magnesium metal, when oxidized in this manner, expands and increases its dimensions approximately 100 percent over its dimensions in the metallic state. As a result of the expansion of the magnesium hydroxide, the split portion 4 of the terminal is expanded or pressed firmly into engagement with the turns of the helical resistor 2. 75

As shown in Figs. 3 and 4 of the drawings, the body portion 7 and the head of the pin 6 are substantially circular in section. However, the body portion may be oval or elliptical in section, as shown in Figs. 5 and 6. If 80 the body portion of the pin 6 is made elliptical or oval in section, as shown in Figs. 5 and 6, the pin may be wedged between the split portion 4 of the terminal and still leave clearance between the walls of the split portion 4 and the body portion of the pin so that steam may pass therethrough to convert the pin to magnesium hydroxide. 95

The terminal construction, shown in Fig. 1, is particularly adapted to tubular heat- 100

ing elements of the type shown in Figs. 7 and 8. In Fig. 7 of the drawing, a heating element 9 is illustrated in the process of manufacture, and, in Fig. 8, the heating element 9 is shown in its completed form.

The heating element 9 comprises, in its unfinished state, the helical resistor 2 having a core 10 of magnesium metal, the terminals 1 having the split end portions 4 inserted into the ends of the helical resistor 2, a tube or sheath 11 enclosing the resistor 2 and the portions 4 and 5 of the terminals, and a helix 12 of magnesium metal, centrally located about the terminals and resistor and placed within the sheath or tube 11.

In order to convert the pins 6, the core 10, and the helix 12 to magnesium hydroxide, the heating element assembly may be placed in an autoclave 13, one end thereof being 20 wedgedly secured in an aperture 14 provided in a partition wall 15. Steam may be admitted into a compartment 16 to the left of the partition 15 through a valve 17 and discharged into a chamber 18 to the right of the 25 partition 15 and exhausted therefrom through a valve 19. Steam, entering the chamber 16 through the valve 17, will flow through the tube or sheath 11 and through an opening 21 in the terminals 1, as indicated by the 30 arrows in Fig. 7. When the magnesium pins 6, the magnesium core 10 and the helix 12 have been subjected to an atmosphere of steam, maintained at a pressure of a predetermined value for a predetermined length of 35 time, the magnesium metal is converted into magnesium hydroxide. The hydroxide of magnesium may then be changed to magnesium oxide by subsequently heating the heating element in a furnace to evaporate the 40 water contained in the hydroxide.

The magnesium metal, when so oxidized, expands and fills the space between the resistor and the walls of the tube 11 compactly, as shown in Fig. 8. As there shown, the pins 6 expand, when converted to oxide, causing the portions of the split end 4 to be expanded or spread apart and press tightly against the end turns of the helical resistor 2. It is to be noted also that, since the magnesium 45 helix 12, when oxidized to magnesium oxide, completely fills the space between the walls of the tube 11 and the ends of the helical resistor 2 in contact with the terminal portions 4, the end turns of the helical resistor will 50 be pressed against the split end portions 4 of the terminals, thereby increasing the pressure exerted between the helical resistor and the terminals by means of the oxide produced by the pins 6.

Since the portion of the magnesium helix 55 12 surrounding the enlarged portion 5 of the terminal 1, tends to oxidize more quickly than the magnesium located to the right thereof, the space between the tube and the portion 60 5 will be filled by the converted magnesium.

thereby restricting the flow of steam through the tube. But, as the terminal 1 is provided with the opening 21, steam will flow through the opening 21 and escape through the tube or sheath 11 by way of the split portion 4 of the terminal, whereby complete oxidation 70 of the magnesium is insured.

While I have indicated that the split end portion 4 of the terminal 1 may be expanded by chemical means, that is, by means of a pin 75 of metallic magnesium placed in the end thereof and oxidized, which upon oxidizing expands the split portion 4 into engagement with the resistor helix 2, it is to be understood that the split portion 4 of the terminal may 80 be expanded by mechanical means.

Since the portion 5 of the terminal 1 is knurled, the oxide 12a will embed itself in the surface of this portion and hold the terminal firmly in position in the tube, as 85 shown in Fig. 8. When the tubular heating unit 9 has been completely treated in the manner hereinbefore set forth, the ends of the tube may be filled with a cement 23, such as water glass. The oxide 12a is then protected from the moisture of the atmosphere and is also prevented from being broken and escaping from the tube 11.

In some instances, it may be desirable to provide the split portion 4 of the terminal 1 90 with screw threads 24, as shown in Fig. 9. If provided with screw threads, the terminal may be threaded onto the resistor helix 2 and the magnesium pins, of the type shown in 95 Figs. 3 to 6, inclusive, inserted, as shown in Figs. 1 and 7, to be subsequently oxidized by 100 steam to convert the same to magnesium oxide, whereby the split portion is expanded into engagement with the resistor helix.

It is obvious from the drawings and the 105 above description, that the terminal 1 is expanded into engagement with the helical resistor 2 by means of the magnesium pin 6 converted to magnesium hydroxide, and that the terminals are secured firmly to the tube or 110 sheath 11 by the expansively oxidized magnesium provided by the helix 12.

The oxide produced by the helix 12 expands within the tube 11 and, in addition to holding the terminals 1 firmly in place, presses 115 the resistor against the split portions 4 of the terminals.

The oxide of magnesium provides the proper insulation between the resistor element, the terminals, and the tube 11, and, also, an 120 efficient path for the flow of heat from the resistor to the tube.

As various modifications may be made in the device embodying my invention without departing from the spirit and scope thereof, it 125 is desired that only such limitations shall be placed thereon as are imposed by the prior art and the appended claims.

I claim as my invention:

1. The method of securing a terminal hav- 130

ing a split end portion to a helically-wound resistor, which comprises inserting a pin of metallic magnesium in the split portion, locating the split portion inside of a helically-wound resistor and subjecting the assembly to the action of steam under pressure to change the metallic magnesium into magnesium hydroxide and cause it to expand and wedge the split portion in the resistor helix.

10 2. The method of securing a tubular terminal having a longitudinally split end portion to a helically-wound resistor adapted to be located in a tubular casing, which comprises the steps of locating a pin of magnesium 15 in the split end portion of the terminal, locating the terminal in an end portion of a helically-wound resistor, locating an open helix of metallic magnesium around the resistor and terminal, locating the assembly within a tubular casing and subjecting it to the action of steam under pressure.

3. A terminal structure for a tubular heating unit having a tubular casing and a helically-wound resistor therein, said terminal 25 including a tubular metal member having a longitudinally-split end portion adapted to be located within a helically-wound resistor, and electric-insulating material expansively oxidized in situ, within and around the split end 30 portion to hold the terminal in proper operative position in a casing and to clamp it in engaging relation with a resistor.

In testimony whereof, I have hereunto subscribed my name this 26th day of June, 1928.
